UNITED STATES PATENT OFFICE.

WILLIAM H. BUNTING, OF TOLEDO, OHIO, ASSIGNOR TO THE BUNTING BRASS, & BRONZE COMPANY, OF TOLEDO, OHIO, A CORPORATION OF OHIO.

MEANS FOR FORMING BEARING-SURFACES.

1,318,537.

Specification of Letters Patent. Patented Oct. 14, 1919.

Application filed January 12, 1917. Serial No. 142,002.

To all whom it may concern:

Be it known that I, WILLIAM H. BUNTING, a citizen of the United States, and a resident of Toledo, in the county of Lucas and 5 State of Ohio, have invented a certain new and useful Means for Forming Bearing-Surfaces; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this 15 specification.

My invention relates to means for forming bearings having compacted surfaces.

The object of the invention is to provide a means which will form from the rough 20 casting of the bearing a cylindrical surface which will have an axis coincident with the axis of the exterior surface of the bearing and subsequently compacting the surface of the bearing thus prepared, which results 25 may be readily produced in the single movement of the said means.

The invention may be contained in different forms of constructions for different purposes, all of which come within the pur- 30 view of my claims hereinafter appended.

To show the practicability of my invention I have selected one of such constructions as an example and shall describe it hereinafter. The construction selected is 35 illustrated in the accompanying drawing.

Figure 1 of the drawing is a side view of a device containing my invention. Fig. 2 illustrates a transverse sectional view of the device showing cutting lips for operating 40 on the bearing preparatory to finishing the surface in advance of the compacting operation. Fig. 3 is an end view of the device. Fig. 4 is a side view of the device showing sectionally the shelf or table of a press and 45 a plunger for operating the device. Fig. 5 illustrates a stripper block used to hold the bearing. Fig. 6 is a sectional view of a modified form of bearing surface forming device.

50 In the use of the device it is operated by a plunger while the bearing casting which is operated on is placed on a shelf or table top of a press. Fig. 4, is a shelf or table preferably having a recess for centering the

bearing with respect to the plunger 3, which 55 operates upon the means 2 for surfacing the bearing and compacting the surface. If the means operates on the bearings in the return stroke of the plunger as well as the forward stroke, a stripper block 32 is provided. The block 32 is bolted by the bolts 33 to the shelf 1. It is substantially semi-cylindrical in form and is provided with two inwardly extending flanges 34 and 35. The flange 34 operates to center the bushing 65 or bearing 6 with respect to the plunger 3 when the bearing is slipped into the stripping block 32. The inner edge of the lower end of the bearing preferably extends over the edge of the opening 4 formed in the 70 shelf 1. The flange 35 extends over the upper end of the bearing 6 to engage and hold the bearing while the plunger 3 is making its return stroke. The means for surfacing the bearing and compacting the surface thus passes through the bearing 6 and the opening 4 in its strokes back and forth.

If it is desired to return the means for compacting the bearing surface through the bearing, the plunger 3 is provided with an 80 extension 36 which passes through the compacting means 2 and is secured thereto by the nut 37. The stripping block 32 may be used when the means for preparing the surface of the bearing and for compacting 85 the surface thereof is moved relative to the table 1. On the other hand, if desired, the means for compacting the surface may be fixed relative to the table 1 and the bearing moved over the means for compacting the 90 surface of the bearing.

The means shown in the drawing is for forming and compacting the inner surface of the bearing. It is made of a single cylindrical member which may be moved relative 95 to the bearing. It may be fixed with respect to the shelf or press and the bearing moved over the cylindrical member, or the bearing may be fixed relative to the shelf or press, and the bearing moved over the member.

The means 2 for forming the bearing surface is provided with preferably a corrugated or fluted pilot 20 having preferably $\frac{1}{2}$ " cuts or flutes 21. The number of such flutes will, of course, vary according to the 105 size of the bearing. The flutes or cuts formed in the pilot 1 may be varied in size likewise according to the diameter of the

bearing and according to the condition of the castings and according to the alloy of which the bearing is composed. The object of the flutes or cuts is to enable the operator to place the bearing relative to the member or the member relative to the bearing so that the axis of the member will be coincident with the axis of the bearing, and to prevent a slight displacement of the bearing or member relative to the bearing by reason of any roughness of surface that may be found near the upper edge of the bearing. The bearing may be so placed that the flutes or cuts will spread at least a portion of the irregularities.

Above the fluted pilot are located a plurality of cutting members or ridges. One or more of the ridges are fluted or channeled and form cutting lips having cutting edges. 20 In the construction shown the ridges immediately following the pilot are provided with cutting lips. The cutting lips of one are located out of alignment with the cutting lips of those that immediately precede, so 25 that the projection of the lips on a plane at right angles to the axis of the means for forming the bearing surface will produce substantially a complete circle. The lips, however, may be so formed that the projections will be disposed a short distance from each other. In such case when the means for forming the bearing surface is moved relative to the bearing, a slight amount of metal in the form of ridges or parts of ridges 30 will be formed after the ridges having the cutting lips have passed any particular point of the bearing, which ridges, or portions thereof, will have surfaces in the line of movement of the ends of the lips. The 35 lips of each ridge thus operate to cut portions of the irregularities on the surface of the bearing, while at the same time permitting the fluted pilot to keep the means for forming the bearing surface substantially in 40 alignment with the axis of the bearing, which could not be done so well if the cutting edge of the ridges were continuous. The lips also operate to cut portions of the bearing and provide clearance for chips that 45 are formed by the movement of the bearing or the means for forming the bearing relative to each other. The lips also provide means for cutting any extreme irregularities which would be cut with great difficulty by a 50 ridge having a cutting edge extending completely around the ridge. Furthermore, the arrangement of the cutting lips provides a means whereby the cutting operation will be substantially uniform throughout the 55 travel of the bearing relative to the means for forming the bearing surface, that is, the cutting lips being divided over a plurality of cutting ridges, the irregularities met with by the lips will be correspondingly divided 60 between the cutting ridges, which permits 65

the operation to be produced under a substantially uniform pressure to move the bearing and means relative to each other.

In the form of the invention shown in Fig. 1, the ridges 24 are provided with the cutting lips 25, the projections of which on a plane at right angles to the means for forming the bearing surface are slightly displaced from each other. In cutting, the formed channels separated by narrow ridges 70 on the inner surface of the bearing extend lengthwise of the bearing. These ridges, however, are cut and removed from the interior of the bearing by the cutting edges located on members or ridges disposed behind 75 the ridges 24. The projections of the ends of the lips 25 being displaced and so that the lips leave longitudinal ridges in the inner surface of the bearing, twisting of the bearing relative to the member is prevented as it 80 gives to both ends of each lip substantially the same work to do, while if a complete cut was made by the ridges of the members having the lips one end of each lip of ridges other than the first would have to cut along 85 a lateral surface, which would not be required of the opposite end of the lip.

In the form of construction shown a plurality of ridges 26 are located on the cylindrical member 2 behind the ridges 24 and 90 are provided with the cutting edges 28. Following the ridges 26 is a member 30 having a square cutting edge 29 backed by a relatively broad cylindrical surface, which 95 operates to give a polishing shave off the bearing and as a burnisher and a pilot. It secures the bearing and the member 2 in position relative to each other during the compacting operation.

Behind the pilot 30 are located members 100 having compacting surfaces or beaded surfaces which operate to compact the surface of the bearing to form a compacted skin within the bearing. In the form of the invention shown the beads 31 are formed on 110 the member 2, and as the member 2 and the bearing are moved one with respect to the other the compacting beads operate successively upon the surface of the bearing which has been prepared by the cutting 115 ridges 24 and 26 and the pilot 30. They successively compress the surface and form a compacted skin which decreases in its compactness and hardness from the surface of the bearing toward the interior of the metal 120 of which the bearing is formed.

A pilot 40 follows the beads 31 and finishes the compacting operation. It is the same size as the last of the beads 31, or a trifle larger in diameter. It also forms a guide 125 for the beads, when the member 2 is connected with means for causing its return through the bearing. The stroke of the plunger 3 is preferably such as to force the member 2 through the bushing to a point 130

that the lower edge of the bushing will extend over the upper edge of the pilot 40. Upon the return stroke the bushing will be operated upon by the flat surface 40 and by the beads, and the member 2 will be guided by the pilot 40.

The diameters of the several parts of the bearing surface cutting and compacting means increase by very small fractions of an inch from the pilot. The circles of the edges of the lips 25 of the ridges 24 are substantially the same and slightly larger in diameter than the pilot 20. The lower ridge 26 may be substantially the same as that of the circle of the edges of the lips 25, particularly if the projections of the lips on a plane at right angles to the axis of the member 2 do not overlap. The succeeding ridge or ridges 26 are of larger diameter than the first ridge 26. The pilot 30 having the square edge 29 is also very slightly larger in diameter than the uppermost ridge 26. The compacting beads preferably increase slightly in diameter over the diameter of the pilot 30, while the pilot 40 is substantially the same as, or a trifle larger in diameter, than the last or uppermost compacting bead 31 of the member 2.

In the form of the invention illustrated in Fig. 6, the projections of the lips 41 on a plane located at right angles to the axis of the means for compacting the surface of bearings overlap so that each succeeding ridge will make a clean cut in the bearing 35 and not leave any longitudinal ridges or portions thereof within the bearing. The following ridge 26 may then be made slightly larger in diameter than the circle of the edges of the lips 41 of the ridges 24.

I claim:

1. In a means for forming surfaces of bearings, the combination of a fluted pilot followed by a plurality of coaxial cutting ridges having successively increased diameters.

2. In a means for forming surfaces of bearings, the combination of a fluted pilot followed by a plurality of coaxial cutting ridges, a following pilot having a broad burnishing surface, a square cutting edge, and a plurality of beads having successively increased diameters.

3. In a means for forming surfaces of bearings, the combination of a fluted pilot followed by a plurality of coaxial cutting ridges having successively increased diameters, a following pilot having a broad burnishing surface, a square cutting edge, a plurality of beads, and a third following pilot.

4. In a means for forming surfaces of bearings, the combination of a fluted pilot followed by a plurality of coaxial cutting ridges, the cutting ridges followed by a second pilot, a third pilot, and compacting

beads having successively increased diameters located intermediate the two last named pilots.

5. In a means for forming surfaces of bearings, a pair of pilots, coaxial compacting 70 beads having successively increased diameters located intermediate and contiguous to the pilots.

6. In a means for forming surfaces of bearings, a pilot, a plurality of coaxial cutting ridges having cutting lips for successively cutting portions of the surface of the bearing, a ridge having a complete circular cutting lip and a member having a square cutting edge and a burnishing surface. 80

7. In a means for forming surfaces of bearings, a pilot, a plurality of coaxial cutting ridges having short cutting lips for successively cutting portions of the surface of the bearing, and ridges having complete 85 circular cutting lips having diameters slightly increased over diameters of the circles of the cutting edges of the lips.

8. In a means for forming surfaces of bearings, a pilot, a plurality of coaxial cutting ridges having short cutting lips for successively cutting portions of the cylindrical surface of the bearing, cutting ridges having diameters slightly increased over 90 diameters of the circles of the cutting edges 95 of the lips, and a pilot following the last named cutting ridges.

9. In a means for forming surfaces of bearings, a pilot, a plurality of coaxial cutting ridges having short cutting lips for 100 successively cutting portions of the surface of the bearing, a complete circular cutting ridge having a diameter slightly increased over diameters of the circles of the cutting edges of the lips, and a member having a 105 square cutting edge and a broad burnishing surface following the last named ridges.

10. In a means for forming surfaces of bearings, a pilot, a plurality of coaxial cutting ridges having cutting lips for successively cutting portions of the surface of the bearing, cutting ridges having diameters slightly increased over 110 diameters of the circles of the cutting edges of the lips, a member having a square cutting edge and a broad burnishing surface following the last 115 named ridges, a second pilot, and beads having diameters successively increased located between the burnishing member and the last named pilot. 120

11. In a means for forming surfaces of bearings, the combination of a pilot, ridges having coaxial cutting lips, the projections of which on a plane at right angles to the axis of the ridges being disposed in spaced 125 relation, a cutting ridge following the ridges having the said cutting lips, a pilot having a square cutting edge and a burnishing surface following the cutting ridge.

12. In a means for forming surfaces of 130

- bearings, the combination of a fluted pilot, a plurality of coaxial ridges having cutting lips for removing portions of material of the bearing in the path of movement of the 5 edges on the lips, a plurality of cutting ridges following the ridges having cutting lips and having successively increased diameter, a plurality of compacting beads having successively increased diameters for compressing the surface of the bearing.
- 10 13. In a means for forming surfaces of bearings, a plurality of coaxial fluted cutting ridges, the channels of each ridge being staggered relative to the channels of the 15 other ridges, the diameters of the cutting edges of the ridges being the same, a circular cutting edge having a diameter slightly increased over that of the fluted ridges.
14. In a means for forming surfaces of 20 bearings, a plurality of coaxial fluted cutting ridges, the channels of each ridge being staggered with respect to the channels of the other ridges, a complete circular cutting ridge located above the fluted ridges.
- 25 15. In a means for forming surfaces of bearings, a plurality of coaxial cutting ridges having short cutting lips for successively cutting contiguous portions of the cylindrical surfaces of the bearings, complete 30 circular cutting ridges having diameters slightly increased over the diameters of the circles of the cutting lips.
16. In a means for forming surfaces of 35 bearings, a plurality of coaxial cutting ridges having short cutting lips for successively cutting contiguous portions of the cylindrical surfaces of the bearings, complete circular cutting ridges having diameters slightly increased over the diameters of the 40 circles of the cutting edges of the lips, pilots preceding and following the cutting ridges.
- 45 17. In a means for forming surfaces of bearings, a plurality of coaxial cutting ridges having short cutting lips for successively cutting contiguous portions of the cylindrical surfaces of the bearings, complete 50 circular cutting ridges having diameters slightly increased over the diameters of the circles of the cutting edges of the lips, pilots preceding and following the cutting ridges, the pilot following the cutting ridges having a square cutting edge.
- 55 18. In a means for forming surfaces of bearings, a plurality of coaxial cutting ridges having short cutting lips for successively cutting contiguous portions of the cylindrical surfaces of the bearings, complete 60 circular cutting ridges having diameters slightly increased over the diameters of the circles of the cutting edges of the lips, pilots preceding and following the cutting ridges, the pilot following the cutting ridges having a square cutting edge.
- 65 19. In a means for forming surfaces for bearings, a fluted pilot followed by a plurality of coaxial fluted cutting ridges, the channels of each ridge being staggered relative to the channels of the other ridges.
- 70 20. In a means for forming surfaces for bearings, the combination of a fluted pilot followed by a plurality of coaxial cutting ridges, a following pilot having a broad burnishing surface and a continuous cutting edge, and a plurality of beads having a successively increased diameter.
- 75 21. In a means for forming surfaces for bearings, a fluted pilot, a plurality of coaxial cutting ridges having cutting edges for successively cutting portions of the surface of the bearings, a member having a continuous cutting edge and a burnishing surface.
- 80 22. In a means for forming surfaces for bearings, the combination of a plurality of coaxial cutting ridges for successively cutting portions of the surface of the bearing, a member having a continuous square cutting edge and a broad burnishing surface following the cutting ridges.
- 85 23. In a means for forming surfaces for bearings, a plurality of coaxial fluted cutting edges located in spaced relation to each other, the channels of the leading ridges being in line with the cutting edges of the following ridges.
- 90 24. In a means for forming surfaces for bearings having a plurality of ridges having coaxial cutting edges, one of the leading cutting ridges being fluted and the channels of the leading ridge being in line with the cutting edge of a following ridge.
- 95 25. In a broach, the combination of a plurality of ridges having cutting edges and channels extending across the ridges and parallel to the axis of the broach, the channels in consecutive ridges being located in 100 staggered relation.
- 105 26. In a broach, the combination of a plurality of ridges having cutting edges and channels extending across the ridges and parallel to the axis of the broach, the channels in consecutive ridges being located in 110 staggered relation, and a following ridge having an unbroken edge.

In testimony whereof I have hereunto signed my name to this specification.

WILLIAM H. BUNTING.
